O. AVERY.

Buttonhole Guide for Sewing Machines.

No. 15,872.

Patented Oct. 14, 1856.

UNITED STATES PATENT OFFICE.

OTIS AVERY, OF BETHANY, PENNSYLVANIA.

IMPROVEMENT IN GUIDES FOR WORKING BUTTON-HOLES.

Specification forming part of Letters Patent No. 15,872, dated October 14, 1856.

To all whom it may concern:

Be it known that I, OTIS AVERY, of the town of Bethany, county of Wayne, State of Pennsylvania, have invented a new and useful Instrument to be used in the Construction of Button-Holes; and I declare that the following is a full, clear, and exact description of the same, reference being had to the accompanying drawings, and to the letters and figures marked thereon.

The nature of my invention consists in attaching to a clasp of any convenient size to be held in the hand, and which embraces the cloth in which the button-hole is to be made or worked, an instrument for catching the thread and twisting the loop of the same, so as to make the button-hole stitch. One edge of the clasp is placed at a proper distance from the side of the button-hole, and serves as a guide for the depth of the stitch which is taken by hand with a common needle. On the face or working side of the clasp is a sliding plate which carries a revolving tweezers or nippers. This plate traverses on the clasp on a line with the button-hole. The tweezers move transversely to the movement of the sliding plate, and are capable of being slid or extended out over the edge of the clasp to catch the thread, and on drawing them back their rotary motion gives the thread the proper loop to make the button-hole stitch.

To enable others to make and use my invention, I will proceed to describe its construction and operation.

The clasp is made about two inches long, exclusive of the hinge, and about one inch wide.

Letter A is a perspective view of the instrument. Letter B is a longitudinal elevation. Letter C is a transverse section.

Figure 1 is the tube in which the tweezers revolve, showing the spiral groove to give the tweezers their rotary motion. Fig. 2 is the tweezers, which may be made of any elastic substance, with a pin to fit into the spiral groove of the tube, and is moved by a thumb-piece sliding on the top of the tube, with a pin connecting with the tweezers, as represented by Fig. 3.

The clasp may be held together by any suitable device, such as a screw, spring, or by a latch, as represented by Fig. 4. Fig. 5 is the traversing plate, which moves in grooves made in the plate of the clasp and carries the tweezers to the working-point in the operation of making the button-hole.

I do not confine myself to the use of the spiral groove in the tube to give a rotary motion to the tweezers, as that motion may be given by making a twist or screw to the tweezers; or they may be revolved by the thumb while in the act of moving the tweezers back and forth to catch the thread.

What I claim as my invention, and desire to secure by Letters Patent, is—

The combination of the sliding plate with the revolving tweezers, operating and arranged substantially in the manner and for the purpose hereinbefore set forth.

OTIS AVERY.

In presence of—

CHAS. AVERY,
M. C. ADDOMS.
